CONVERTIBLE ARTICLE OF FURNITURE

Louis I. Cohn and Albin J. Brinkman, Philadelphia, Pa., assignors to Spiers Bedding Corporation, Philadelphia, Pa., a corporation of Pennsylvania

Application December 29, 1936, Serial No. 118,162

1 Claim. (Cl. 5—20)

This invention relates to a convertible article of furniture and has for its object to provide, in a manner as hereinafter set forth, an article of the class referred to capable of being conveniently converted from a studio couch into a bed.

A further object of the invention is to provide, in a manner as hereinafter set forth, a convertible article of furniture including an outer section and an inner section, the former constituting a housing for normally closing the latter and of bed height. The inner section is capable of being disposed in extended relation with respect to the outer section and it includes a pivoted element for swinging to a position to make the inner section of bed height and to coact with the outer section to form a bed.

A further object of the invention is to provide, in a manner as hereinafter set forth, a convertible article of furniture capable of being conveniently converted from a studio couch into a bed and with the article so constructed whereby a seven-inch inner-spring mattress can be used as an element thereof in lieu of an inner-spring mattress of four or five inches as now generally employed in articles of the class to which this invention belongs.

A further object of the invention is to provide, in a manner as hereinafter set forth, an article of furniture of the class referred to including a normally housed frame for a turnable carrier means for an inner-spring mattress, and a foldable support connected with the carrier means and providing when the frame is in extended relation with respect to its housing means what may be termed a fifth leg for supporting the carrier means horizontally from the transverse center of the latter to position the mattress thereon at bed height.

A further object of the invention is to provide, in a manner as hereinafter set forth, an article of furniture in the class referred to including an inner mattress supporting frame and with the latter so formed as to provide for a mattress of increased length to be used with respect to the length of the mattresses now employed in articles of the class to which this invention belongs.

A further object of the invention is to provide, in a manner as hereinafter set forth, an article of furniture of the class referred to including a stationary section and a shiftable section and with the shiftable section having as an element thereof a foldable combined head rest and a supporting leg for supporting the shiftable section substantially at the transverse center of the latter.

A further object of the invention is to provide, in a manner as hereinafter set forth, a convertible article of furniture of the class referred to including an outer section of bed height and an inner section capable of being easily shifted from within the outer section and extended to bed height whereby the said sections coact to provide a bed.

A further object of the invention is to provide, in a manner as hereinafter set forth, a convertible article of furniture of the class referred to including what may be termed an upper spring mattress preferably of seven inches high and a lower spring mattress preferably seven inches high and with means whereby the inner-spring mattress may be easily positioned and supported flush with the top of the upper spring mattress and with the mattresses coacting to provide a bed.

Further objects of the invention are to provide in a manner as hereinafter set forth, a convertible article of furniture of the class referred to which is simple in its construction and arrangement, strong, durable, compact, expeditiously and conveniently converted from a studio couch into a bed, readily assembled, and comparatively inexpensive to manufacture and lighter in weight with respect to the articles of the class to which this invention belongs.

With the foregoing and other objects in view, the invention consists of the novel construction, combination and arrangement of parts as will be more specifically described and are as illustrated in the accompanying drawings wherein is shown an embodiment of the invention, but it is to be understood that changes, variations and modifications may be resorted to which fall within the scope of the invention as claimed.

In the drawings:

Figure 1 is an elevation of an article of furniture in accordance with this invention looking towards the back thereof.

Figure 2 is a view similar to Figure 1 with the inner section in extended relation to the outer section.

Figure 3 is a view looking towards one side of the article of furniture when extended.

Figure 4 is a section through the inner section of the article on line 4—4, Figure 2.

Figure 5 is a sectional plan on line 5—5, Figure 2.

Figure 6 is a section on line 6—6, Figure 2, of the inner section of the article when extended, and

Figure 7 is a section on line 7—7, Figure 2 of the inner section of the article when extended.

The article of furniture includes a housing or outer section 1 and carried thereby is a covered upper spring mattress 2 preferably of seven inches in height. The mattress is mounted upon the housing 1. The latter is opened at its back as indicated at 3. The article of furniture includes an inner section or inner-spring mattress support generally indicated at 4. The inner section 4 is normally housing within the outer section 1. The sections 1 and 4 may be disposed in adjusted relation whereby the section 4 will extend from the back of the section 1 as is shown in Figures 3 and 5. The sections 1 and 4 are slidably connected together and for such purpose a pair of links 5, 6 are employed. The links cross each other and are pivotally connected together as at 7. The link 5 is pivotally connected to the section 1 as at 8 and slidably connected to the section 4 as at 9. The link 6 is slidably connected to the section 1 as at 10 and pivotally connected to the section 4 as at 11. The links are normally housed within the section 1 and are of a length to permit the section 4 to assume the position shown in Figure 5. The section 1 may be pulled forwardly from over the section 4, or the latter may be pulled rearwardly from the open back of the section 1. The latter at each side thereof has supporting legs 12, 13. The section 1 includes a bar 14 arranged therein. The pivot 8 for link 5 is connected to bar 14. A groove 15 is formed in bar 14 for the slidable connection 10. The top of section 1 is in the form of a bed bottom of the spring type, but this is not so shown as it is concealed by the cover of the section 1 and supports the mattress 2.

The section 4 includes a supporting frame formed of a pair of inverted U-shaped side cheeks 16, 17 of like form and each of which is formed from a strap of metallic material of rectangular cross section at any point throughout its length. Each of said side cheeks includes a head 18, a front leg 19 and a rear leg 20. The legs 19 of the cheeks 16, 17 are connected together by a brace bar 21. The pivot 11 of the link 6 is connected to the bar 21. The latter is provided with a slot 22 for the slidable connection 9. The legs 19 of the side cheeks 16, 17 are also connected together by an upper brace bar 23. The legs 20 of the cheeks 16, 17 are connected by a lower brace bar 24 which provides a support for the inner mattress to be referred to when the section 4 is housed. The bar 23 is arranged at the upper end of the front of said structure and constitutes a support for a purpose to be referred to. That portion of the back of said structure above the bar 24 provides a passage for a purpose to be referred to.

The section 4 includes a pair of oppositely disposed angle irons 25, 26 disposed in transverse relation with respect to section 4 and each of which includes a vertical leg 27 and a horizontal leg 28 extending inwardly from the upper end of the leg 27. Between the transverse center and outer end of the angle irons 25, 26 there are provided pivots 29, 30 respectively which are connected to the heads 18 of the cheek members at the vertical medians of said heads whereby the angle irons 25, 26, are eccentrically pivoted at the sides thereof to the cheek members and in this connection attention is directed to Figure 3. Each of the angle irons provides what may be termed a carrier which is normally disposed in an inverted position. When in inverted position the carriers constitute suspensions for a spring bed bottom to be referred to and when moved

from normal to righted position provide supports for holding the bed bottom horizontally in upwardly extended relation with respect to the heads 18 of the side cheeks. Spacing means 31 are mounted on the pivots 29, 30 and interposed between the cheek members and the angle irons 25, 26. When the angle irons 25, 26 are in the position shown in Figure 3, the rear ends thereof are spaced forwardly of the legs 20 and the forward ends thereof are spaced forwardly from the legs 19. When the irons 25, 26 are in the position shown in Figure 3, they extend in close proximity to the back of section 1, but the legs 19 of the cheek members are spaced from such back.

Fixedly secured to and bodily movable with the irons 25, 26 is a bed bottom 32 upon which is suitably connected a spring mattress 33 of a height corresponding to the mattress 2. The irons 25, 26 in connection with the bed bottom 32 form a rotary holder for the mattress 33. The holder is to be selectively shifted to right side up and right side down positions for respectively supporting mattress 33 above the side cheeks 16, 17 and for suspending it below the tops of and between said cheeks. Preferably the mattress 33 will be seven inches in height.

Fixed to the lower face of the bed bottom 32 is a pair of oppositely disposed spaced parallel angle-shaped brackets 34 which are disposed on the transverse median of bed bottom 32. Pivotally connected to the brackets 34 is a leg forming member 35 formed from a strap of metallic material to provide a skeleton leg 36 substantially of triangular contour and a stretch 37 which extends at right angles from the upper end of the inner portion of leg 36. The outer portion of leg 36 is pivotally connected to one of the brackets 34 as at 38. The free end of the stretch 37 is connected to the other bracket 34 as at 39. Secured to the lower face of the bed bottom 32 between the brackets 34 and cheek member 17 is a transversely disposed bar 40 having its ends formed with depending flanges 41, 42. Pivotally connected to the flanges 41, 42 is a foldable and extendible skeleton head rest forming element 43 which provides a means for shifting the leg 36 to and from supporting position and also functions as a retaining means for the mattress 33. The element 43 includes a head portion 44, side portions 45, 46 and a link 47. The side portion 45 is of less length than the side portion 46. The upper part of the side portion 46 is formed of a pair of stretches 48, 49 disposed at opposite inclinations and with the stretch 49 merging into one end of the head portion 44. The stretch 48 is inturned at its lower end as at 50 and loosely extends through the flange 42. The inturned portion of the stretch 48 merges into a depending stretch 51 which has one end of the link 47 pivotally connected therewith as at 52. The other end of the link 47 is pivotally connected as at 53 to the outer portion 54 of the leg 36. The side portion 45 of element 43 is of a contour similar to that of the stretches 48, 49 of the side portion 46 and the lower end of side portion 45 is inturned as at 55 and pivotally connected to the flange 41. The head portion 44, side portion 45 and stretches 48, 49 of side portion 46 coact to provide a head rest forming means and which extends over the mattress 33, as well as being arranged at opposite sides of the latter whereby the mattress is retained on the bed bottom 32.

When section 4 is to be housed within the sec-

tion 1, the rotary holder with mattress 33 thereon is turned from the right side up position (Figure 3) to the right side down position (Figure 1). Prior to the turning of the holder from right side up to right side down the element 43 is shifted from its position (Figure 3) to its position (Figure 1) whereby leg 36 will bear against the lower face of bed bottom 32 and element 43 will bend against mattress 33. When the rotary holder is right side up it rests on pivots 29, leg 36 and bar 23, but when right side down it rests on pivots 29 and bar 24. When element 43 is shifted to the position (Figure 1), link 47 and leg 36 have passed the position of alignment and taken a locking position beyond the dead center where they will stay and hold down element 43 on the mattress until the link 47 and leg 36 are manually released by the shifting of element 43 to the position (Figure 3).
20 When section 4 is arranged in extended relation with respect to the back of section 1 and with section 4 folded in the manner as shown in Figure 1, then bed bottom 32 is turned on its pivots rightside up carrying the mattress 33 therewith. The element 43 is shifted in a manner to assume the position shown in Figure 2 whereby element 35 will be moved in the direction to dispose the leg 36 in supporting position such as shown in Figures 2 and 3. When element 43 is shifted to dispose leg 36 in supporting position the head and side portions of element 43 will be arranged in a manner to provide a head rest such as shown in Figures 2 and 3. The leg 36 constitutes what may be termed a fifth leg for section 4, the other four legs being provided by the cheek members 16, 17. The passage formed on the back of the section 4 provides a clearance for the carriers when they are swung from inverted to righted position and from righted position to

inverted position. When the carriers are turned to righted position they seat on the bar 23.

What we claim is:

In an article of furniture, a frame-like structure having the upper end of its front formed with a support, its top open throughout, the upper portion of its back open throughout to provide a passage and a pair of vertical spaced parallel side cheeks constituting supports therefor, a pair of spaced parallel normally inverted carriers of like form and each of angled contour in cross section to provide a vertical and a horizontal leg, said carrier opposing the upper end portion of the inner faces of said cheeks, means for pivotally connecting said vertical legs to said cheeks, bed forming means fixed to said horizontal legs, said carriers when in inverted position suspending said bed forming means within said structure below the upper ends of said cheeks and when turned to righted position through said passage seating on said support and disposing said bed forming means horizontally above said cheeks, and a shiftable unit forming a foldable and extendible head rest extending across the top of said bed forming means and a foldable and extendible supporting leg for, arranged below and positioned intermediate the ends of said bed forming means, said unit including connections between the head rest and leg to provide for their shifting in unison, said unit being pivotally connected to the bottom of said bed forming means at spaced points of said bottom and when shifted in one direction simultaneously extending said head rest and leg and in the opposite direction simultaneously folding said head rest and leg, said leg when extended to supporting position being disposed below the back of said structure.

LOUIS I. COHN.

ALBIN J. BRINKMAN. 40
